BUILDING CONSTRUCTION

Frank R. Felber, Irvington, N. J.

Application September 20, 1934, Serial No. 744,819

3 Claims. (Cl. 72—1)

This invention relates to a building construction and primarily aims to provide a novel means enabling the use of precast concrete studs, joists, and the other essential beams or elements.

5 The more specific objects and advantages will become apparent from a consideration of the description following taken in connection with accompanying drawings illustrating an operative embodiment.

10 In said drawings:—

Figure 1 is a fragmentary vertical section through the framework of a building illustrating the invention;

Figure 2 is a side elevation of the parts of Figure 1;

Figure 3 is a horizontal sectional view taken on the line 3—3 of Figure 2;

Figure 4 is an elevation of a window frame;

Figure 5 is a vertical cross section taken 20 through the building at a window;

Figure 6 is a horizontal sectional view taken through the building at a window;

Figure 7 is a horizontal sectional view taken on the line 7—7 of Figure 1;

25 Figure 8 is a cross section similar to Figure 7 taken through a modified form;

Figure 9 is a fragmentary side elevation of a stair frame, and

Figure 10 is a horizontal sectional view taken 30 through one of the uprights of a window, of a modified form.

Referring specifically to the drawings, a suitable foundation or base is provided at 10, for instance of either precast or poured cementitious material. From the foundation 10, studs or uprights 11 extend, which are preferably of precast cementitious material. On the base 10, joists preferably of precast cementitious material 12 are disposed and superposed on the upper ends 35 of studs 11 are tie beams 13, of cementitious material. Disposed on the tie beams 13 are studs 14 of the same material and construction as the studs 11 and which in turn have disposed across their upper ends, tie beams 15 of the same material and construction as those at 13.

The joists 12 and the tie beams 13 and 15 are preferably reinforced by one or more longitudinally extending metallic rods or wires 16, the terminals of a lower rod or rods 16 having hooks 50 17 embedded in the cementitious material thereof, being bent around but spaced from short rods 18 extended through openings in adjacent studs, short rods 19 also being passed through openings in the joists 12 and studs 11. Short rods 55 20, similar to those at 19, are passed through

studs 14 and joists 21 for the second story, which joists 21 rest on the tie beams 13.

The studs 11 and 14, have one or a plurality of longitudinally extending reinforcing metallic wires or rods 22 therein which extend beyond the 5 upper and lower ends and fit or are embedded in sockets or openings 23, 24, and 25, in the foundation 10, or tie beams 13 and 15, respectively.

Disposed on the beam 15, are joists 26. Roofing rafters 27 are disposed against the joists 26, 10 being fastened thereto by short pins or rods 28 passing therethrough, a ridge beam 29 being disposed between the rafters 27 of opposite inclination. Said joists 26, and rafters 27 are preferably of precast cementitious material and have 15 one or more longitudinally extending reinforcing rods or wires embedded therein. Such wires 30 of the rafters 27, may have a hook 31 to extend about adjacent rods 28 and at their upper ends project beyond the ends of rafters 27 and 20 into openings or sockets 32 in the ridge beam.

Tie beams 13 and 15 and ridge beam 29 are preferably poured after positioning of the adjacent structural parts, with the aid of forms temporarily attached to such parts, thus insuring 25 accurate fitting and attachment.

The various structural elements particularly adjacent the floors and ceilings may be integral 30 ly and rigidly united together by concrete or cementitious material poured after they are erected, that is in situ like said tie beams 13 and 15 and ridge beam 29, with the aid of course of suitable forms, as at floors 33 and 34, and a ceiling 35, which in some instances may also be a floor, and all of which optionally have a finishing coat 35 as at 36, 37, and 38, respectively.

The various structural elements may have 40 openings therethrough at intervals as at 39 to accommodate braces 40, passage of electrical wires therethrough or the like.

The windows and doors for the structure may be provided in any suitable way, a window frame being shown as at 41 and a door frame may follow the same general construction, with, of course, the sill being stronger. It is obvious 45 that the lintels of the window and door frames may also be round or of any desired shape. This door frame 41 has its side stiles 42 grooved as at 43 and matching the same are grooves 44 in adjacent studs 11, so that cementitious material 45 may be poured therebetween to key and fasten them together. The frame 41 is preferably reinforced by one or more wires or rods 46 and has grooves 47 to accommodate the mounting 50 of the sash or sashes.

As shown in Figure 9, stairs 48 may be precast from cementitious material into the desired form and fastened in place in any suitable manner and usually by means engaging reinforcing wires or rods 49 embedded therein.

All of the various structural elements described, where necessary, have fasteners 50 which are embedded in the cementitious material and usually coiled as at 51 around the adjacent reinforced rods or wires and which extend beyond the opposite side of the respective elements to provide free bendable terminals 52. By means of such terminals, metallic lathing or the like 53 is secured against the interior surface of the frame so that plastering or the like 54 may be applied thereto. On the exterior of the framework, any suitable finishing material may be secured in place by the adjacent bendable terminals 52, such as slabs 55 of any suitable material, and for instance of brick veneering, the same having anchors 56 engaged by such terminals. Optionally, metal lathing 57 may be secured against the exterior surface of the adjacent terminals 52, having mortar 58 applied between the same and the surface elements 55.

Hip and valley beams where necessary in the construction of the roof may be cast in place in the same manner and of the same construction as ridge beam 29.

30 As suggested in Figure 10, the surfacing panels, veneering or the like 55, may be omitted, and the surface 58 constitutes an exterior stucco.

In lieu of the wire 50 being of the form shown in detail in Figure 7, it may be flat as suggested in Figure 8 and have openings therein through which the wires pass. In this connection, the flat wire or fastening element is designated 50', the stud 11', the reinforcing rods thereof as 22', and the openings through the fastening wire 50' as 40 51'.

Various changes may be resorted to provided they fall within the spirit and scope of the invention.

I claim as my invention:

1. A building construction element of precast cementitious material having reinforcing rods therein projecting beyond the exterior surface of the concrete to facilitate attachment to adjacent parts, and a multiplicity of relatively close metallic wire fastening elements for lathing or the like embedded in the cementitious material and having bendable portions extending beyond the lathing-engaging surface of the construction element, said fastening elements being coiled above the rods whereby they are interconnected. 5 10

2. A building framework having structural elements of precast cementitious material, said elements having longitudinally extending reinforcing members therein, said reinforcing members extending beyond the ends of certain of the structural members and interfitted into adjacent structural members, additional structural members engaged with the first mentioned structural 20 members, and pins extending through the additional structural members and the adjacent first mentioned structural members, certain of the longitudinal reinforcing members having hooks engaging adjacent fastening elements. 25

3. A building framework having structural elements of precast cementitious material, said elements having longitudinally extending reinforcing members therein, said reinforcing members extending beyond the ends of certain of the 30 structural members and interfitted into adjacent structural members, additional structural members engaged with the first mentioned structural members, and pins extending through the additional structural members and the adjacent first 35 mentioned structural members, the corner structural elements having three sections in engagement with each other, with the intermediate section offset from the other to provide an interior, 40 angular corner.

FRANK R. FELBER.
